(57) **CLAIM**

The ornamental design for an air freshener device, as shown and described.

DESCRIPTION

FIG. 1 is a perspective view of the front of the air freshener device (portions not claimed shown with broken lines).

FIG. 2 is a perspective view of the rear of the air freshener device (portions not claimed shown with broken lines).

FIG. 3 is a plan view of the front of the air freshener device (portions not claimed shown with broken lines).

FIG. 4 is a plan view of the rear of the air freshener device (portions not claimed shown with broken lines).

FIG. 5 is a plan view of the top of the air freshener device (portions not claimed shown with broken lines).

FIG. 6 is a plan view of the bottom of the air freshener device (portions not claimed shown with broken lines).

FIG. 7 is a plan view of one side of the air freshener device (portions not claimed shown with broken lines); and,

FIG. 8 is a plan view of the other side of the air freshener device (portions not claimed shown with broken lines).

The broken line showing the air freshener coupled with the ornamental design in FIGS. 1-8 is for illustrative purposes only and forms no part of the claimed design.
